UNITED STATES PATENT OFFICE.

SWAN E. MOREN, OF BIWABIK, MINNESOTA.

BRIQUET-MACHINE.

1,306,309.

Specification of Letters Patent. Patented June 10, 1919.

Application filed October 10, 1918. Serial No. 257,606.

To all whom it may concern:

Be it known that I, SWAN E. MOREN, a citizen of the United States, residing at Biwabik, in the county of St. Louis and 5 State of Minnesota, have invented certain new and useful Improvements in Briquet-Machines, of which the following is a specification.

This invention seeks to provide a machine 10 which may be built at a low cost and operated economically and efficiently to produce briquets of peat or other material. The invention seeks to provide a machine for the stated purpose in which the briquets will 15 be firmly compressed and provision made for preventing breakage to the operating parts in the event that large rocks or other non-compressible foreign matters should be contained in the material being treated, and 20 a further object of the invention is to provide efficient means for effecting discharge of the formed briquet. Other incidental objects of the invention will appear in the course of the following description and it 25 is to be understood that the details of construction shown in the accompanying drawings are illustrative only and that various changes may be made therein without involving any departure from the spirit or 30 scope of the invention as the same is defined in the claims following the detailed description.

In the accompanying drawings—

Figure 1 is a side elevation with parts 35 broken away and parts in section of a machine embodying my invention;

Fig. 2 is a plan view of the same;

Fig. 3 is a longitudinal section on the line 3—3 of Fig. 2, showing the working 40 parts in position to receive a charge of material;

Fig. 4 is a similar view showing the position of the parts just prior to the completion of the compression stroke of the plunger;

Fig. 5 is a similar view showing the position of the parts immediately prior to the discharge of the briquet;

Fig. 6 is a detail perspective view of the 50 plunger;

Fig. 7 is a detail perspective view of the compressing cylinder.

The supporting frame 1 of the machine may be of any convenient or preferred construction and while I have illustrated a sin-

gle compressing mechanism, it is to be understood that the construction permits duplication of the operating mechanism so that the invention may be operated in gangs driven from a common shaft. In the illustrated embodiment of the invention, longitudinal rails 2 are secured upon the upper side of the supporting frame 1 and at one end of the frame bearings 3 are provided upon these rails and a driving shaft 4 is 60 journaled in said bearings. Motion may be imparted to the driving shaft from any convenient source of power and upon the said shaft is a pinion 5 meshing with a larger gear 6 which is secured upon the end of a 65 crank shaft 7 journaled in suitable bearings 8 upon the rails 2. Between the gear 6 and the side of the frame or the adjacent rail 2, a tappet 9 is secured upon the crank shaft 7 and this tappet 9 is adapted to impinge 70 upon a trigger 10 which is carried by the upper arm 11 of an angle lever which is fulcrumed upon a pin 12 on the side of the rail 2, as clearly shown. The lower or 75 depending arm of this angle lever is turned laterally, as shown at 13, so as to extend under the rail 2 and has its extremity turned downwardly in the median longitudinal plane of the machine. The trigger 10 is 80 pivoted between its ends within a notch or bifurcation in the arm 11 and the upper 85 edge of the trigger is straight, while the lower edge thereof is curved at its ends, as clearly shown in Fig. 1. It will also be noted upon reference to Fig. 1 that the 90 straight flat upper edge 14 of the trigger bears against the top plate 15 of the arm 11 so that when the gear wheel 6 is rotated in the direction indicated by the arrow in Fig. 1 the tappet 9 will impinge against the outer end of the trigger and will thereby 95 oscillate the angle lever to which the trigger is pivoted, but if the gear wheel should be rotated in the opposite direction the trigger will yield to the impact of the tappet and will not actuate the angle lever so that breakage of the parts will be avoided. A link 16 100 is pivoted to the lower end of the angle lever and extends longitudinally of the machine, as shown, the end of the link remote from the lever being pivoted to the lower end of an oscillatory bar 17 which is fulcrumed between brackets 18, depending from the frame, and has its upper end formed into a curved rack 19 which meshes with a rack 105 20

on the under side of the compressing cylinder 21.

The end of the frame remote from the driving shaft 4 is constructed to provide an 5 abutment 22 and the inner opposed faces of the side rails immediately adjacent the inner 10 face of said abutment are recessed, as shown at 23, so as to receive and hold a removable 15 jaw or compressing block 24. The inner 20 face of the said jaw is provided with a cavity or recess 25 in which the material may be compressed and an ejector 26 is seated in the base of said recess and yieldably held projected into the recess by a leaf 25 spring 27 which is mounted in a recess 28 in the outer face of said jaw and bears upon 30 stem 29 extending through the jaw or block from the ejector, as clearly shown in Fig. 3. The compressing cylinder 21 is open at both 35 ends and is provided at diametrically opposite points with projections or lugs 30 resting upon and slideable on the bottoms of recesses 31 formed in the side rails 2, as clearly shown in Fig. 1, while caps 32 are secured 40 upon the side rails so as to extend over the said recesses and thereby hold the said lugs upon the bases of the recesses 31. The cylinder is thus permitted to reciprocate 45 longitudinally of the frame and is held against rotation about its own axis, and it is normally held at the forward limit of its movement by springs 33 which are disposed at the sides of the machine and are connected at their opposite ends to the forward guide 50 lugs 30 and to suitable brackets or projections 34 on the sides of the machine. The action of the segmental gear 19 and the rack 20 is to retract the cylinder in opposition to the springs 33 as will be presently more fully 55 set forth. Upon its upper side, the compressing cylinder carries a hopper 35 through which the material to be compressed is fed into the cylinder in advance of the plunger and the material may be supplied to this hopper from any convenient form of conveyer or other feeding device or if the machine be set up for domestic use the material may be fed manually to the hopper.

The plunger consists of a forward member 60 56 and a rear member 37 which are of such diameter as to fit closely within the compressing cylinder, but capable of movement longitudinally within the cylinder. The forward member 36 of the plunger has its 65 forward end provided with a recess 38 corresponding to the recess 25 in the jaw 24 and is also constructed with an axial cavity 39 which receives a reduced extension 40 from the front end of the plunger member 37. A longitudinal slot 41 is formed through the 70 extension 40 and a pin 42 is carried by the forward member 36 and extends through the 75 said slot so as to guide the rear member 37 and prevent relative rotary movement between the plunger members. A spring 43 is coiled

around the extension 40 between the member 37 and the member 36 and this spring should be of sufficient strength to hold the members normally in extended relation, it being designed to yield only when a large rock or other hard foreign substance happens to be within the material fed into the compressing cylinder. The rear end of the rear plunger member 37 is pivotally connected to a pitman 44 which has its rear end mounted upon the crank of the shaft 7, as shown, and as will be readily understood. The plunger member may be pivoted directly to the end of the pitman as will be readily understood, but in order to provide for a variation in the size of the briquet without disassembling the parts of the machine, I employ the connection illustrated in the accompanying drawings in which the plunger member is constructed with a threaded socket 45 at its rear end which is engaged by a screw 46 having an eye 47 at its rear end to receive the pivot pin or pintle 48 inserted through the said eye and the end of the pitman, as shown. A lock nut 49 is mounted upon the screw 50 46 and is adapted to be turned home against the rear end of the plunger member so that by turning the nut home to hold the screw in the adjusted position, the stroke of the plunger may be regulated to produce briquets of any desired size.

It is thought the operation will be readily understood. The material to be compressed is fed into the hopper 35 with the parts in the position shown in Fig. 3 and will, of course, pass into the compressing cylinder adjacent and in advance of the front end of the forward plunger member 36. The driving shaft will rotate continuously and the gearing is so timed that immediately after a charge of material has been deposited in front of the plunger the crank shaft 7 will begin to drive the pitman forward so that the plunger will advance and force the material against the jaw 24. At the instant 100 that the plunger completes its forward stroke and thereby accomplishes the compression operation, the tappet 9 will engage the trigger 10 so that the angle lever will be swung about its pivot 12 and the link 16 moved forwardly so as to swing the bar 17 and cause the segmental gear 19 to act upon the rack 20 and retract the cylinder. The plunger will simultaneously start to move rearwardly but the segmental gear 19 and rack 20 will cause the cylinder to move more rapidly than the plunger so that an open space will be formed between the cylinder and the jaw 24, as shown in Fig. 5, and consequently the formed brick or block will drop from the machine and may be received by any convenient form of conveyer. When the plunger moves forwardly so as to compress the material the ejector 26 will, of course, be moved forwardly so that the 115 120 125 130

spring 27 carrying the ejector will be put under tension. When the plunger and cylinder start to move rearwardly, the tension upon the spring will, of course, be released 5 and the ejector will then be moved rearwardly slightly but sufficiently to loosen the formed brick from the jaw 24 so that it will be discharged immediately upon the withdrawal of the cylinder from the jaw, and in- 10asmuch as the cylinder will move rearwardly faster than the plunger, the plunger will at this time serve as an ejector so that the discharge of the brick will be certain. The rotation of the crank shaft will, of course, carry the tappet 9 past the trigger 14, whereupon the springs 33 will at once contract and pull the cylinder to its forward position ready to receive a fresh charge of material, but the plunger will continue to 20 retract until its front end is in the same plane as the rear edge of the exit from the hopper 35 or in rear of said plane to permit the material fed into the hopper to pass directly into the cylinder. A second compression stroke will then be effected and the 25 operation repeated indefinitely.

It will be readily noted that the parts of my machine are simple in construction and compactly arranged. The machine may be 30 operated at a high speed without liability to breakage and is free of complicated arrangements so that it will prove durable and the cost of upkeep will be negligible.

Having thus described my invention, what 35 is claimed as new is:

1. A machine for the purpose set forth comprising a stationary jaw, a plunger movable toward and from the jaw, a cylinder housing the plunger and yieldably held 40 against said jaw, and means for retracting the cylinder from the jaw when the plunger moves from the same and at a higher speed than the plunger.

2. A machine for the purpose set forth 45 comprising a stationary pressure-receiving member, compressing elements arranged to compress material against said member, one of said elements constituting a container for the compressed material and means for with- 50 drawing said container-forming compressing element from said stationary pressure receiving member whereby to discharge the compressed material.

3. In a machine for the purpose set forth, 55 the combination of a stationary jaw, an ejector mounted in the jaw, a cylinder normally abutting the jaw, a plunger mounted in the cylinder and movable toward and from said jaw, and means for retracting the 60 cylinder from the jaw.

4. In a machine for the purpose set forth, 65 the combination of a stationary jaw, an open-ended cylinder normally abutting the jaw, a plunger slidably mounted in the cylinder, a hopper carried by the cylinder,

means for reciprocating the plunger, yieldable means for holding the cylinder against the stationary jaw, and an intermittently operating mechanism for retracting the cylinder from the jaw. 70

5. In a machine for the purpose set forth, 75 the combination of a stationary jaw, a slidably mounted open-ended cylinder normally abutting the jaw, a rack on the under side of said cylinder, means for preventing rotation of the cylinder, a gear engaging said rack, a plunger mounted in the cylinder, means for reciprocating the plunger within the cylinder, and means for periodically oscillating the said gear whereby to retract 80 the cylinder from the jaw.

6. In a machine for the purpose set forth, 85 the combination of a supporting frame, a jaw on said frame, a cylinder mounted for limited sliding movement in the frame and held against rotation therein, yieldable means for normally holding the cylinder against the jaw, a plunger slidably mounted in the cylinder, an actuating shaft, operative connections between said shaft and the 90 plunger, a lever mounted upon the frame, a trigger carried by the rear end of said lever, means for preventing movement of the trigger relative to the lever in one direction, a tappet upon the actuating shaft adapted 95 to engage said trigger, and operative connections between said lever and the cylinder whereby the cylinder will be periodically retracted from the jaw.

7. In a machine for the purpose set forth, 100 the combination of a supporting frame, a stationary jaw on said frame, a cylinder slidably mounted upon the frame and normally abutting said jaw, means for periodically retracting the cylinder from the jaw, 105 a plunger slidably mounted in the cylinder and consisting of yieldably connected forward and rear members, and means acting on the rear member to reciprocate the plunger. 110

8. In a machine for the purpose set forth, 115 the combination of a supporting frame, a cylinder slidably mounted thereon, yieldable means for holding the cylinder normally in a forward position, means for periodically retracting the cylinder, a plunger mounted in the cylinder and comprising a forward section having an axial bore, a rear section having a reduced extension at its front end fitting in said bore 120 and provided with a longitudinal slot, a spring coiled around said extension between the plunger sections, a pin carried by the forward plunger section and passing through the said longitudinal slot, and means for reciprocating the plunger. 125

9. In a machine for the purpose set forth, 130 the combination of a slidably mounted cylinder, means for yieldably holding the cylinder normally in its forward position,

means for periodically retracting the cylinder, a plunger slidably mounted in the cylinder and having a threaded socket at its rear end, a screw engaged in said socket, a lock nut mounted on said screw and adapted to be turned home against the end of the plunger, a pitman pivoted to the outer end of said screw, and means for actuating said pitman.

10. In a machine for the purpose set forth, the combination of a supporting frame, a stationary pressure-receiving jaw

on the frame, a cylinder slidably mounted on the frame to abut said jaw, means for holding the cylinder normally against the 15 jaw, an operating shaft, means whereby upon rotation of said shaft in one direction the cylinder will be retracted, said means being inoperative to move the cylinder upon rotation of the shaft in the opposite direction, and a plunger actuated by said shaft and mounted within the cylinder.

In testimony whereof I affix my signature.
SWAN E. MOREN. [I. S. S.]
